UNITED STATES PATENT OFFICE.

SAMUEL E. VAN HORN, OF MANHASSET, NEW YORK.

FLOAT FOR BOATS.

1,352,770.

Specification of Letters Patent. Patented Sept. 14, 1920.

Application filed February 21, 1919, Serial No. 278,378. Renewed March 26, 1920. Serial No. 369,047.

To all whom it may concern:

Be it known that I, SAMUEL E. VAN HORN, a citizen of the United States, residing at Manhasset, county of Nassau, and State of New York, have invented certain new and useful Improvements in Floats for Boats, of which the following is a specification.

This invention relates to floats for boats and small vessels, and has for its object to provide means to support said boats on or above the level of the water when from any cause they are in a sinking condition; a further object of the invention is to construct such means in such a manner that they may be maintained in a closed position when not in use, thereby taking up but little room, and so that they will instantly open upon the submerging of the boat, and prevent the latter from entirely sinking.

These and other objects of my invention are set forth in the following specifications, and shown in the accompanying drawings, which form a material part of this disclosure and in which:—

Figure 1 is a transverse sectional view of a boat showing my invention applied thereto, and in its open position;

Fig. 2 is a top plan view of one of my improved floats;

Fig. 3 is a transverse sectional view taken on the line 3—3 of Fig. 2; and,

Fig. 4 is a side elevational view of one of my improved floats in its closed position.

In carrying my invention into practice I attach outriggers to the sides of the boats. These outriggers may be as many in number as desired, according to the size and weight of the boat. Such outriggers are preferably rectangular in form, having horizontal members 10, and vertical depending members 11, which extend downwardly from the outer end of said outriggers and are pivotally attached thereto, as at 14. My floats are attached to the vertical member 11, and extend toward the water when the boat is floating thereon.

My floats are constructed of strong rubberized fabric 15 in the form of an umbrella

or parachute, and may be secured to the 50 said vertical member in any desired manner, such, for example, as by ribs 16 secured to said fabric, said ribs having eyes 17 in their upper ends, through which an assembling wire 18 passes to secure them together 55 in operative position, the vertical member 11 having cross-ribs or arms 19, 19, which in turn are secured to the wire 18.

Strips 25 of buoyant material such as cork are fastened to the lower ends of the ribs 16. 60

A buoyant ring 20, filled with air or other buoyant material, is secured to a sleeve 21 which loosely incloses the lower end of the vertical member 11, and is adapted to slide thereon. The upper portion of the sleeve 65 21 is provided with eyes 22, in which are pivotally secured the lower ends of the ribs 23 the upper ends of which are pivotally secured in eyes 24 secured to the ribs 16, in such manner that as the sleeve 21 is 70 raised on the member 11 by the action of the ring 20, the said ribs and the fabric 15 carried thereby will be distended in the form of an umbrella.

As shown in Fig. 1, my floats will automatically close when the ring 20 does not touch the water and will normally remain in this position. The moment the boat commences to sink, and my floats strike the water, they will be opened automatically by 75 the action of the strips 25 and the ring 20, resulting in confining more or less air between the fabric 15 and the water which is prevented from escapement by said fabric, so that an efficient means is provided for 80 maintaining the boat above the water and preventing its sinking.

It will be understood, of course, that these floats are arranged upon both sides of the boat so as to prevent the capsizing of the 85 boat.

What I claim as my invention and desire to secure by Letters Patent is:—

1. Floats for boats formed of water-proofed flexible material arranged in the 90 form of an umbrella, and adapted to open to act as a float upon striking the water.

2. Floats for boats comprising a body

of waterproofed flexible material, radial reinforcing members secured thereto, said floats being arranged in the form of an umbrella, and adapted to be maintained in a closed position normally, but to open automatically upon striking the water.

3. Floats for boats comprising outriggers secured to said boats, floats formed of waterproofed flexible material secured to

said outriggers, reinforcing members and ribs therefor, said floats being adapted to normally remain closed and to open automatically upon striking water.

In testimony whereof, I, SAMUEL E. VAN HORN, have signed my name to this specification.

SAMUEL E. VAN HORN.
